CLAIM

The ornamental design for a security camera, as shown and described.

DESCRIPTION

FIG. 1 is a front perspective view of a security camera according to the present design;

FIG. 2 is a front elevational view of the security camera of FIG. 1;

FIG. 3 is a rear elevational view of the security camera of FIG. 1;

FIG. 4 is a left-side elevational view of the security camera of FIG. 1, the right-side elevational view being a mirror image thereof;

FIG. 5 is a top plan view of the security camera of FIG. 1; and,

FIG. 6 is a bottom plan view of the security camera of FIG. 1.

The broken lines depict portions of the security camera in which the design is embodied that form no part of the claimed design.
